RESISTOR ELEMENT

Edwin E. Arnold, Pittsburgh, Pa., assignor to
Westinghouse Electric & Manufacturing Com-
pany, East Pittsburgh, Pa., a corporation of
Pennsylvania

Application June 15, 1935, Serial No. 26,848

6 Claims. (Cl. 201—69)

This invention is related to the resistor element used in a heater element of the strip type.

Heater elements of the strip type frequently consist of a resistor element in the midst of insulating material. The resistor element and insulating material are frequently compressed together and often are enclosed in a protective armor. Failure in a heating element has heretofore frequently been due to irregular contact between the resistor element and the surrounding insulating material. Such irregularity is likely to produce overheating of the element at spots, which materially lessens the life of the element.

It is an object of this invention to produce a resistor element which can be more readily and securely bonded with the insulating material in the heater element.

It is a further object of this invention to produce a resistor element which will be inexpensive to manufacture, can readily be made with automatic machinery and will require no special skill to unite it with the insulating material of the heater element.

It is a further object of this invention to provide a resistor element which shall resist motion through the resistor material in any direction with a greater resistance than would be offered by only the edges of a ribbon of the same area as the resistor element.

Other objects of my invention and details of the construction and of the method used to construct the element will be apparent from the following detailed description and the accompanying drawing, in which:

Figure 1 is a face view of one form of the resistor element, the left-hand portion being shown in an early stage of its manufacture;

Fig. 2 is a diagrammatic section showing the plunger and die used in making that form of the resistor element shown in Fig. 1;

Fig. 3 is a similar view showing the plunger at the completion of its stroke;

Fig. 4 is a face view similar to Fig. 1 of an alternative form of a resistor element;

Fig. 5 is a view similar to Fig. 2, illustrating the die and plunger used for the manufacture of that form of the resistor shown in Fig. 4.

Fig. 6 is a view similar to Fig. 3, showing the plunger at the completion of its stroke; and

Fig. 7 is a view of a mechanism for making that form of the resistor element shown in Fig. 4.

The resistor element is made of a strip 1 of sheet metal having sufficient resistance to be suitable for an electric heater. At each end of

the strip 1, a flat portion 2 is provided which may be equipped with holes, projections or any other desired means for providing terminal connections. As my invention is not related to these provisions, they are not illustrated or further described.

The main portion of the strip is slotted alternately from opposite edges to constitute a zigzag ribbon. The slits shown at 3 from one edge and at 4 from the other edge are in staggered relation, whereby the transverse portions 5 are united only at their ends. The uniting portions, such as 6, are flat with the plane of the strip 1.

The transverse portions 5 are twisted so that they occupy a position at right angles to said plane. The twists illustrated at 7 and 8 at opposite ends of any one transverse portion 5 are in opposite senses, but twists adjacent the same connecting portion 6 may be in opposite senses, as illustrated in Fig. 1, or may be in the same sense, as illustrated in Fig. 4.

The resistor element thus formed is of great flexibility. It can be deflected at an angle to the plane of the strip 1 with as great ease as if the transverse members 5 were in the same plane 25 as said strip. It can be deflected in said plane with great ease because of the position of the transverse members at right angles to that plane. It can be stretched or twisted, or, to a lesser degree, compressed without distortion of the metal itself to any significant extent. It thus adapts itself readily to any deformation required in incorporating it into a body of insulating material. Particularly, it can be easily bent into a circular shape for use in annular heaters. Also, when the finished heater element is bent, it can follow the bending without producing strains in the surrounding material.

The effective thickness of the resistor element in the central part is the width of the transverse portions. Although they do not completely occupy all the space in this thickness, the space needed to accommodate the resistor element is of this thickness. The portions 6 on the other hand form when considered all together a pair of margins for the element of no more thickness than the metal itself.

In the manufacture of that form of the resistor element shown in Fig. 1, it is preferably 50 moved step by step along a rack composed of supporting teeth 10 and a uniting structure. Cooperating with the rack is a plunger equipped with teeth 11 and a uniting body 12. The strip 1 is in position for the die to work when each slit, such

as 4, is positioned in the middle of the face of a supporting tooth 10 and the slots from the opposite edge of the strip 1, such as the slot 3, are each midway between two supporting teeth. As 5 the plunger descends, each transverse member 5 is acted upon in a downward direction on one edge by a tooth 11 of the plunger and in an upward direction on the opposite edge by a supporting tooth 10. Each strip 5 is thus twisted, 10 the sense of the twist being opposite for any two adjacent strips. The strip 1 may be stepped forward between each successive stroke of the die until the whole length of the strip has been acted upon or a plunger and a supporting rack of sufficient length to act upon the whole strip at once 15 may be provided and the resistor element finished in one stroke.

In making the form of resistor strip illustrated in Fig. 4, a rack having supporting teeth 16 and 20 a connecting portion as illustrated in Fig. 5 is used. The coating plunger is equipped with teeth 15, a corner 17 of each tooth being beveled. The operation of this die is similar to that illustrated in Figs. 2 and 3. The strip 1, when it is 25 in position for the die to work, is supported upon the teeth 16 so that the faces of these teeth contact the strips 5 adjacent to but not at an edge, the supported edge being on the same side for each strip. The teeth 15 contact the middle of 30 the unsupported portion of the strips and as the plunger descends all of the strips are twisted in the same sense. As the twisting occurs, the edge of the strip nearest the supporting face of the tooth 16 rises, and in order to provide for this 35 motion of said edge, the corners 17 of the plunger teeth have been beveled, as shown.

Another form of mechanism for twisting the transverse strips of the resistor 1 is illustrated in Fig. 7. It comprises a supporting rack having 40 supporting teeth 20 and a connecting body. Co-operating with this rack is a pinion 21. In the operation of this mechanism, if the pinion rotates in the direction indicated by the curved arrow, the rack 20 and the strip 1 will be moved 45 toward the left or the pinion will be moved toward the right. If the machine designer so desires, he may provide for both of these elements to move. As this motion occurs, the teeth of the pinion contact with the transverse member 5. 50 As illustrated at 22, the side face of a tooth contacts the transverse portion 5 being twisted throughout nearly the full width of said portion. As the pinion continues to rotate, the transverse portion is forced into a twisted position until 55 the lower part of it contacts with the side face of the supporting tooth 20 as illustrated at 23. As the motion continues beyond this point, a shoulder 24 of the tooth drags across a portion of the face of the twisted portion.

60 It will be observed that in this operation of the mechanism, there is very little ineffective contact between the teeth of the pinion and the strips. It is possible to twist the strips by the 65 mechanism illustrated in Fig. 7 operating in the opposite sense, but when this is done, the bending action of the teeth of the pinion is performed almost entirely by the shoulders of the teeth and the result is poor efficiency. The preferred direction for the travel of the rack and the strip 70

is such that the supported edges of the transverse portions 5 are the forward edges.

I do not desire to be limited to resistor elements made by the mechanical methods described herein, since the resistor elements will possess 5 the same desirable qualities if made by any suitable mechanical method.

I claim as my invention:

1. A conductive resistor element comprising a sinuous ribbon of sheet metal having transverse 10 portions each in a plane normal to the plane of the element, margin portions joining each pair of successive transverse portions the margin portions being in a plane parallel to the plane of the element, said transverse portions having torsionally twisted portions, one at each end of each transverse portion uniting it to the respective margin portions.

2. A conductive resistor element having two series of marginal portions, the members of each 20 series being spaced away from the adjacent members of that series and all members of both series being in one substantially flat surface, said resistor element also having connecting members each joining one of said marginal portions in one 25 series to the succeeding member of the other series, said connecting members being so torsionally twisted that, except at their junction with the marginal portions they are at an angle to said flat surface.

3. A conductive resistor element having two series of marginal portions, the members of each 30 series being spaced away from the adjacent members of that series and all members of both series being in one substantially flat surface, said resistor element also having connecting members each joining one of said marginal portions in one 35 series to the succeeding member of the other series, said connecting members being so torsionally twisted that, except at this junction with the marginal portions they are at an angle to said flat surface, the twist being in opposite 40 senses in the twisted portions of each one of the connecting members.

4. A resistor element in the form of a ribbon 45 extending zig-zag from side to side of the element and having two twisted portions in each traverse from one side to the other, said twisted portions being near the sides of the resistor element and the portion of the ribbon between them 50 being untwisted.

5. A resistor element in the form of a ribbon 55 extending zig-zag from side to side of the element and having two twisted portions in each traverse from one side to the other, said twisted portions being near the sides of the resistor and the portion of the ribbon between them being 60 untwisted, the portions of the ribbon between one traverse and the next also being untwisted.

6. A resistor element in the form of a ribbon 65 extending zig-zag from side to side of the element and having two twisted portions in each traverse from one side to the other, said twisted portions being near the sides of the resistor and the portion of the ribbon between them being 70 untwisted, the portions of the ribbon between one traverse and the next also being untwisted, and in a plane at an angle to the first-named untwisted portion.

EDWIN E. ARNOLD. 70
